AUTOMATIC HUMIDOR

Raymond A. Yates, Rockville, Md.

Application March 26, 1941, Serial No. 385,356

3 Claims. (Cl. 226—125)

My invention relates to humidors and has as one of the principal objects thereof the provision of a humidor so constructed and arranged whereby pipes and the like may be readily filled with tobacco therefrom.

Another object of my invention is to provide a humidor or device of the above described character equipped with means for tamping the tobacco within the bowl of a pipe coincident with the filling of the bowl with the tobacco.

An important object of my invention is to provide a device of the character described which is simple in construction, durable in use, efficient in operation and economical in manufacture.

With the above and other objects in view, as will hereinafter appear, the invention consists in the combination, and arrangement of parts hereinabove set forth and illustrated in the accompanying drawings, from which the several features of the invention and the advantages attained thereby will be readily understood by those skilled in the art.

Referring to the drawings wherein like reference characters designate like parts throughout the several views:

Figure 1 is a perspective view of my invention.

Figure 2 is a sectional view taken on the line 2—2 of Figure 1.

Figure 3 is a detail vertical sectional view illustrating the parts in pipe filling and tamping positions.

Figure 4 is a sectional view taken substantially on the line 4—4 of Figure 2.

Figure 5 is a detail vertical sectional view of the upper end of the humidor and illustrating the sponge container and latch member.

As illustrated in the drawings, I provide a substantially horizontally disposed base 5 having secured to one side thereof an upwardly extending support 6, the latter being attached to the base 5 by means of a plate-like member 7. The upper face of the base is recessed to accommodate therein an ash tray 8 and is provided on opposite sides of said ash tray with projections constituting match box retainers 9 over which are disposed the lower ends of open match boxes, one of which is illustrated in dotted lines in Figure 1.

Superjacent the base 5, the support 6 has fixed thereto a humidor 10 comprising upper and lower sections 11 and 12 respectively and with the lower section telescopically mounted within the upper section for vertical movement therein. The lower end of the lower section is closed by

5 a bottom wall 13 formed with a centrally disposed aperture in which is disposed the lower restricted end section 14 of a funnel 15, the latter constituting a discharge hopper and having its upper end provided with a flange fixed to the side walls of the lower section 12 for vertical movement with said section. The upper end of the upper section is fixed to the support 6 and is normally closed by a lid 16, the latter being 10 pivotally connected to the support by means of a hinge 17.

The underface of the lid 16, adjacent the front wall 18 of the section 11, has attached thereto a perforated casing 19 in which is contained a 15 sponge 20, or the like, adapted to be saturated with a suitable liquid for moistening tobacco contained within the humidor, it being understood that tobacco is introduced into the humidor by raising the lid 16, a suitable finger-piece 21 being attached to said lid to facilitate the raising thereof. The front wall 22 of the casing 19 is hinged to the bottom by means of a hinge 23 whereby access may be had to the casing for replacing the sponge.

25 The underface of the lid 16, overlying the front wall 18 of the section 11, has secured thereto the right angularly disposed upper end 24 of a resilient latch member 25, the latter having its body portion normally disposed in appressed relation with the front face of the wall 18 and formed, adjacent its lower end, with a key-hole slot 26 through which extends a headed pin 27 carried by the wall 18. The lower end of the member 25 is formed with an arciform finger-piece spaced from the wall 18 to facilitate release of the member 25 from the pin 27 when sufficient pressure is applied to the lid to position the head of the pin 27 within the confines of the enlarged portion of the key-hole slot as hereinafter set forth.

30 The upper end 24 of the member 25, at the jointure with the body portion, is fashioned with an incurvated section 28 in which is normally seated the outer end of a flange 29, the inner end of said flange 29 being structurally integrally formed with the upper end of the front wall 22 of the casing 19 as clearly illustrated in Figure 5. That portion of the upper face of the wall 18 over which the flange 29 is disposed, is recessed to permit downward movement of the lid when pressure is applied thereto to effect disengagement of the member 25 from the pin 27 as heretofore described.

35 The underface of the bottom wall 13 is provided with a pair of spaced laterally disposed

guides 30 in which is slidably mounted the marginal sides of a closure plate 31 normally closing the lower end of the section 14 of the hopper 15 as clearly illustrated in Figure 2 of the drawings. The front face or edge of the closure plate 31 is formed with an arciform recess 32 and with a depending flange 33 marginating said recess. The flange 33 is adapted to engage the front portion of the bowl of a pipe P to position said bowl subjacent and in registry with the recess 32 10 for a purpose hereinafter set forth.

The rear face of the plate 31 has connected thereto one side of a substantially U-shaped leaf spring 35, the opposite side of said spring being connected to the rear wall of the lower section 12 for movement therewith. The spring 35 serves to normally maintain the plate in underlying engagement with the lower end of the section 14, which extends a slight distance subjacent the underface of the wall 13, thus closing the lower end of the hopper to preclude discharge of tobacco therefrom. The lower end of the support 6 has connected thereto the lower end of a coil spring 36, the upper end of said spring being connected to the rear face of the bottom wall 13 of the section 12 and serving to normally maintain said sections in extended relation. The support 6, has fixed thereto a stop 37 for engaging the underface of the wall 13 to limit the downward movement of the section 12 by the action of the spring 36.

The upper end of the section 11 is provided with a transverse bar 38 to which is secured the upper end of a substantially cylindriform tamper 39, the lower end of which extends into the hopper 15. The outer faces of each side of the upper section 11 is provided with a pair of spaced upper and lower shelves 40 and 41 respectively constituting a pipe rack. The lower shelves 41 are formed with recesses 42 for receiving the bowls of pipes while the upper shelves 40 are formed with apertures 43 through which the stems of the pipes extend as clearly illustrated in Figure 1 of the drawings.

In use, it being understood that the sections 11 and 12 have tobacco contained therein and that the parts are in the positions illustrated in Figure 2 of the drawings, the bowl of the pipe P is disposed against the flange 33 and moved in a direction towards the spring 35 to actuate the plate towards the support 6 and thus effect registry of the recess 32 with the open end of the section 14 of the hopper. When the parts are thus positioned the bowl of the pipe will be disposed under the section 14 and an amount of tobacco will be discharged therein whereupon the pipe is raised upwardly to effect similar movement of the section 12 with respect to the section 11 and thus agitate tobacco within the sections and cause a further discharge of the same into the bowl of the pipe. As the pipe is moved upwardly with the section 12, the tamper 39 operates as a follower to force tobacco out of the lower end of the hopper and to tamp said tobacco within the bowl of the pipe. When the bowl of the pipe is thus filled, the pipe is lowered and removed from below the section 12 thereby releasing the section 12 and plate 31 for simultaneous movement by the springs 37 and 35 respectively. The springs serve to actuate the lower section downwardly against the stop 37 and the plate 31 forwardly to close the bottom of the section 14 of the hopper respectively. Any tobacco discharged from the hopper in advance of the closing thereof by the plate 31, while the pipe is being removed from

engagement with the flange 33, will be accumulated within the tray 8 from whence it may be deposited within the humidor for use if desired.

From the foregoing, it will be apparent that my humidor not only serves to maintain tobacco contained therein in a moist and desired smokeable condition, but lends itself to the ready filling and tamping of tobacco within the bowl of the pipe. Furthermore, my humidor serves as a means for conveniently storing and supporting pipes when not in use.

Without further elaboration the foregoing will so fully explain the invention that others may, by applying current knowledge, readily adapt the same for use under various conditions of service. Moreover, it is not indispensable that all the features of the invention be used conjointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described as the same is only illustrative of the principles of operation, which are capable of extended application in various forms, and that the invention comprehends all construction within the scope of the claims.

What I claim is:

1. In a device of the character described, a base, a humidor disposed above said base and provided with a pair of relatively movable upper and lower sections, said upper section fixed to said base and said lower section having a discharge opening, a closure plate slidably carried by said lower section and normally closing said opening, said plate provided with a pipe bowl engaging member for operating said plate to open position with respect to said opening when pressure is applied to said member by a pipe to position its bowl in registry with said opening and to move said lower section towards said upper section, a tamper fixed within said upper section and operable to force tobacco through said opening into the bowl and tamp the same within said bowl upon said movement of said lower section, and means for urging said lower section away from said upper section and said plate to closed position with respect to said opening upon removal of said pipe from said member.

2. In a device of the character described, a base, a humidor disposed above said base and provided with a pair of relatively movable upper and lower sections, said upper section fixed to said base and said lower section having a discharge opening formed in its bottom wall, guides carried by said bottom wall, a closure plate slidably mounted in said guides and normally closing said opening, said plate formed with a recess for registry with said opening and provided with a pipe bowl engaging member marginating said recess for operating said plate to effect registry of said recess with said opening when pressure is applied to said member by a pipe bowl to position said bowl in registry with said recess and opening and for moving said lower section towards said upper section to agitate tobacco in said sections, a tamper fixed within said upper section and having its lower end normally disposed above said opening and operable to force tobacco through said opening into the bowl and tamp the same within said bowl upon said movement of said lower section, and spring means for urging said lower section away from said upper

section and said plate to closed position with respect to said opening upon removal of said bowl from said member.

3. In a device of the character described, a container adapted to be disposed above a base and provided with a pair of relatively movable upper and lower sections, with said lower section having a discharge opening, closure means carried by said lower section and normally closing said opening and operable away from said opening when pressure is applied to said means by a receptacle in effecting registry with said opening

5 and moving said lower section towards said upper section for agitating material in said sections, a tamper fixed within said upper section and operable to force material through said opening into the receptacle and tamp the same within said receptacle upon said movement of said lower section, and means for urging said lower section away from said upper section and said closure means to closed position with respect to said opening.

10

RAYMOND A. YATES.
